UNITED STATES PATENT OFFICE.

BURTON C. COONS, OF ROCHESTER, NEW YORK.

PARING-MACHINE

1,168,788.

Specification of Letters Patent. Patented Jan. 18, 1916.

Application filed May 20, 1915. Serial No. 29,273.

To all whom it may concern:

Be it known that I, BURTON C. COONS, of Rochester, in the county of Monroe and State of New York, have invented a new and useful Paring-Machine, fully set forth in the following specification and shown in the accompanying drawings.

The present invention relates to paring machines for apples and other fruit and 10 more particularly to that type in which the article to be pared is rotatively supported and the paring knife is caused to move in the direction of the axis of rotation of the article and at the same time on a curve 15 50 forming to the shape of the article, an object of this invention being to provide a construction in which the knife is caused to assume a position at the inner end of the fork or supporting device that will completely pare the end of the article and do 20 55 away with hand trimming or with special trimming devices.

To this and other ends, the invention consists in certain parts and combinations of 25 60 parts all of which will be hereinafter described, the novel features being pointed out in the appended claims.

In the drawings: Figure 1 is a view of one side of the machine constructed in accordance with this invention; Fig. 2 is a view of the opposite side of the machine; Fig. 3 is an enlarged detailed view showing the knife in its relation to the supporting fork and the turn table, together with adjacent parts; Figs. 4 and 5 are detailed views 30 65 of the driving drum showing the follower in two positions, one before it has shifted in advance of the drum and the other after it has been shifted as will be hereinafter 40 70 pointed out; Fig. 6 is an enlarged detailed view showing the turn-table in one of its extreme positions; Fig. 7 is a detailed sectional view on the line *a—a*, Fig. 3 showing the turn-table in the other extreme position; 45 75 and Fig. 8 is a detailed view showing the cooperation between the improved knife and the supporting fork.

Referring more particularly to the drawings, 1 indicates the main frame having a 50 80 horizontal shaft 2 thereon supporting a reel 3. This reel has three bearing sections 4 integral therewith to which are secured by bolts 5 removable bearing sections 6. One or both of these sections of each bearing is 55 85 cut away at 6^a and, within each bearing, a tubular fork shaft 7 is arranged, the latter

having the fork 8 removably secured at one end and pinion 9 removably secured to the other end. Core ejectors operate within the tubular shafts 7 and are controlled by a 60 stationary cam 10 on the main frame 1 in a manner well known.

The shaft 2 is rotated periodically by a well known means comprising a stopping and driving member 11 having arms corresponding in number to the number of forks on the reel, each arm having a lateral projection 12. Coöoperating with the stop and driving member is a disk 13 provided with a lateral projection 14 and having a smooth 70 75 periphery except for a single notch. In operation, when the reel is not rotating, two of the projections are engaged in the smooth periphery of the disk 13, but, at a certain point in the movement of the disk, the projection 14 enters between the arms of the stopping and drive member 11 causing one of the projections 12 to enter the notch in the member 13 and, by this coöperation, effecting the completion of the movement of 80 85 the three armed stopping and driving member, two of the projections 12 eventually again coöperating with the smooth periphery of the disk 11. The disk 13 has a pinion 15 rigid therewith and this pinion is driven by a pinion 16 which, in turn, meshes with a pinion, not shown, arranged on the shaft of the driving drum 17.

The driving drum has a gear 18 secured thereto and meshing with a gear 19 on the 90 95 drive shaft 20 to which the drive pulley 21 is secured. Also arranged on the drive shaft 20 is a gear 22 which meshes with a small pinion 23 arranged on one end of a shaft 24, said shaft 24 extending horizontally 95 across the machine and having a pinion 25 at its other end for rotating the forks, the pinions 9 on said forks being presented successively to the pinion 25 to be driven by the latter.

The main frame 1 is provided with a horizontal extension 26 at one side of and above the reel, and, extending from the opposite side of the machine to the outer end of said extension, is a guide rod 27 on which the carriage 28 operates, said carriage also being guided on the shaft 24 by means of a depending arm 29. The guide is so arranged that the carriage may be moved back and forth longitudinally of the fork, this movement preferably being produced by means of a follower 30 which operates within a 100 105 110

way 31 formed about the drum 17. At the outer end of this carriage 28 a bracket 32 is secured by bolts 32^a and on this bracket the knife turn-table is mounted to swing. This 5 turn-table preferably embodies a shaft 33 turning in bearings 34 on the bracket 32 and having, at its upper end, a knife supporting arm 35 and, at its lower end, a slotted knife guiding arm 36. The knife stem or rod 37 is 10 removably and pivotally supported at 38 on the knife supporting arm 35 and is guided in the slotted arm 36, a spring 39 being adjustably secured at one end to the lateral extension 40 and being attached at the other 15 end at 41 to the guide arm 36, said spring yieldingly holding the knife toward the article being pared. At the lower end of the stem 37, a head 42 is secured, this head being provided with the usual knife guard 43 and 20 with a knife 44. This knife is of novel construction having a recess or notch 45 in one end thereof in order that the knife may be brought in close proximity to a paring fork 8 as shown in Fig. 8 so that the knife edge 25 46 will lie above the axis of rotation of the fork. The knife head is also formed with a depressed portion as at 47 in line with the notch in the end of the knife for the same reason. Not only does the depression in the 30 head and the notch in the knife permit the knife to be brought close to the fork for the purpose of insuring a better trimming of the article in proximity to the core, but, at the same time, all danger of engagement between 35 the tines of the fork and the adjacent corner of the knife blade is eliminated.

With the end in view of effecting the oscillation or swinging of the turn-table at the proper times, driving connection is established 40 between the turn-table and the main frame. In this instance, this driving connection is in the form of a segmental gear 48 on the guide arm 36 meshing with the rack 49 formed on the bracket 50 which is secured by bolts 51 to the main frame extension 26. As the engagement between the 45 gear 48 and the rack 49 occurs only during a portion of the movement of the carriage 28, it is desirable to hold the turn-table 50 against oscillation during the remaining portions in order that the knife may be in proper position to coöperate with the ends of the article on the paring fork. With this 55 in view, the guide arm 36 on the turn-table is provided with two converging faces 52 which are spaced at 53 from the end teeth on the gear 48 and which are less in height than the teeth of the gear 48 as will be seen by referring to Fig. 3. The bracket 50 is also provided 60 with guide faces indicated at 54 and these guide faces are in a plane with the bases of the teeth on the rack and are designed for coöperation with the guide faces 52 after the gear 48 has passed out of engagement with 65 the rack 49, the guide faces 54 extending in

opposite directions from the rack 49 and being of less height than said rack. To still further prevent the turning of the turn-table, the bracket 50 carries two guide faces 55 arranged above the guide faces 54 and in 70 a plane with or substantially in a plane with the ends of the teeth of the rack 49 for co-operation with the end teeth on the gear 48 after said teeth have passed out of engagement with the rack. 75

Heretofore, even when machines of this type have been new, the difficulty of getting the paring knife close to the fork at the ends of the movement of the knife has caused the improper paring of the ends of 80 the articles. With the wearing of the driving connection between the turn-table and the main frame, this difficulty has increased and, as a consequence, with old machines a ring of the outer skin has been left on the 85 fruit about the core, thus necessitating the employment of special help or trimmers for removing this unpared portion or the provision of a trimming attachment on the paring machines. To overcome the disadvantage of this wearing action, there has been provided, in this invention spring means which acts upon the turn-table to take up this wear and to maintain the faces 52 and 54 in engagement after the gear 48 90 has passed out of engagement with the rack 49. In this instance, this spring means embodies a U-shaped member 56 having one arm slotted at 57 and secured by the bolt 32^a, the other arm being free and bearing 95 against a cam member 58 which is secured to the shaft 33. This cam member 58 has a central curved portion which, when engaging the spring, produces no action on the turn-table, but at the ends of this curved portion are shoulders 59 which, when engaged by the spring, hold the turn-table 100 against the guides 54 on the main frame. The cam member also has an arm 58^a which acts as a knife stop by limiting the inward movement of the knife stem. This spring 105 also performs another function. It bears upon one of the shoulders 59 as the turn-table approaches the position shown in Fig. 7 and shifts the turn-table together with its 110 supporting carriage 28 in advance of the driving mechanism, this being due to the engagement of the turn-table with the rack on the main frame. This will be seen clearly 115 shown in Figs. 4 and 5 where the follower 120 30 is shown in the position it occupies immediately before the turn-table advances ahead of the drum and also immediately after the follower has been shifted, the 125 groove or way 31 in the drum 17 being enlarged at this point to permit a lost motion between the drum and the carriage which it drives. By this arrangement, the carriage and the turn-table may stand still a short 130 time after the gear 48 has been disengaged 130

from the rack 49 so that the knife will have time to completely pare the inner end of the article and to a certain extent flatten the same before being carried away from the article. After it has remained still for the above purpose, it must move away from the article very quickly and to this end the way 31 is provided with a sharp or abrupt bend 60 which produces this action.

10 The machine may also be provided with a coring attachment of any suitable construction, that shown herein being one of known form and therefore no claims are made thereto. It comprises a coring spoon or 15 blade 61 carried by a holder 62 which is adjustably secured by bolts 63 to a support 64, the latter being pivotally supported at 20 65 on the carriage 28 and being movable on a guide 66 carried by the main frame, so as 25 to direct the coring spoon to an article while it is being pared in order to cut the core therefrom and to withdraw the article from the fork after paring. A pushoff 67 pivoted at 30 68 rides over the article on the fork when 35 the carriage moves in one direction and upon the movement of the carriage in the other direction to carry the coring spoon 61 away from the fork, this pushoff assists the coring spoon in removing the pared article from the fork. After the article has been removed, the supporting member 64 turns about the axis 65 by reason of the engagement of the carriage 64 with the projection 69, thus causing the article to be stripped 40 from the spoon 61 by the doffer 70.

In the operation of the device, the fruit or article is placed by hand upon one of the forks 8 while the latter is out of paring position. The rotation of the reel 3 brings this 45 fork in the path of the coring spoon 61 so that the fork will be driven by the gear 25. About this time, the paring knife which has been located adjacent the outer end of the fork, begins to move toward the article substantially in line with the axis of the latter 50 by reason of the engagement of one of the faces 52 with one of the guide faces 54. Shortly before the gear 48 engages the rack 49, the knife will be in engagement with the 55 article to be pared, the knife yielding to correspond to the size of the article. When the gear 48 engages the rack 49, the knife begins to move toward the inner end of the fork in an arc corresponding to the size of the article, the rotation of the fork causing the skin to be removed in a spiral path about 60 the article. About the time the end of the article is reached, that is, about the time the gear 48 is about to become disengaged with the rack 49, the spring 56 acts on the turn-table and the carriage 28 in such a way as to advance the carriage ahead of the driving drum in the manner hereinbefore described, thus permitting the carriage to remain 65 stationary for a short period while the

knife is paring the inner end of the article. The abrupt shoulder 60 then comes into operation and quickly removes the knife away from the article, permitting the coring spoon to complete its inward movement to 70 cut the core after which the coring spoon is withdrawn carrying the article off the fork and the core, the latter being then ejected from the fork in the manner described.

According to this invention, all wear in 75 the driving connection between the turn-table and the main frame is automatically taken up by a spring so that the guides on the turn table are held against the guides on the main frame, thus providing a better paring of the ends of the articles. A new form 80 of driving connection between the turn-table and the carriage is provided which is not liable to breakage and which insures the turn table against turning while the gear 85 and rack are disengaged. The spring which takes up the wear in the driving connection between the turn-table and the main frame, also serves to shift the turn-table, and the carriage which supports it, ahead of the 90 driving mechanism so that it is possible to hold the turn-table knife at the inner end of the article for insuring a complete paring of the article and a flattening of such end, a flattened end being desirable when 95 the articles are to be sliced. This arrangement operates even though the knife head be adjusted to operate upon those articles which are not forced to the base of the tines of the fork, it having been found that when 100 the usual paring machine is adjusted to operate on articles so positioned, it will effectively pare the ends of articles which are forced on the fork to the base of the tines or vice versa. It will also be noted 105 that the knife head and the knife have been formed and arranged so that it is possible to have the corner of the knife operate in close proximity to the fork without injury to the fork or the knife by engagement of 110 such parts so that a better paring of the inner end of the article is obtained.

What I claim as my invention and desire to secure by Letters Patent is:

1. In combination in a paring machine, a 115 main frame, a rotary fork for supporting an apple during the paring thereof, a carriage movable in the direction of the length of the fork, a turn-table mounted on said carriage, driving connection between the turn-table and the main frame, a knife carried by said turn-table, and spring means acting on the turn-table to hold the same against loose movement at the limits of its movements.

2. In combination in a paring machine, a 125 main frame, a rotary fork for supporting an apple during the paring thereof, a carriage movable in the direction of the length of the fork, a turn-table mounted on said carriage, a knife carried by the turn-table, a gear on 130

the turn-table, a rack on the main frame, guides on opposite sides of the rack, and a spring acting on the turn-table to hold the latter against the guides after it has passed 5 out of engagement with the rack.

3. In combination in a paring machine, a main frame, a rotary fork for supporting an apple during the paring thereof, a carriage movable in the direction of the length of the fork, a turn-table mounted on said carriage, a knife carried by the turn-table, a gear on the turn-table, guide faces arranged on said turn-table on opposite sides of the gear, a rack arranged on the main frame and engaged by the gear, guide faces on opposite sides of the rack, and a spring acting to hold one of the guide faces on the turn-table against one of the guide faces on the main frame after the gear has disengaged with 20 the rack.

4. In combination in a paring machine, a main frame, a rotary fork for supporting an apple during the paring thereof, a carriage movable in the direction of the length of the fork, a turn-table mounted on said carriage, a knife carried by the turn-table, a gear on the turn-table, converging faces arranged on the turn-table on opposite sides of the gear, a rack arranged on the main frame and engaged by the gear, guide faces on opposite sides of the rack, and a spring acting to hold one of the converging faces against one of the guide faces after the gear has disengaged with the rack.

5. In combination in a paring machine, a main frame, a rotary fork for supporting an apple during the paring thereof, a carriage movable in the direction of the length of the fork, a turn-table mounted on said carriage, a knife carried by the turn-table, a gear on said turn-table, guide faces arranged on said turn-table on opposite sides of the gear, the width of the guide faces being less than the width of the teeth of the gear and the 40 ends of the guide faces being spaced from the gear teeth, a rack arranged on the main frame for engagement by the gear teeth and two guide faces arranged on each side of the rack, one of said guide faces being in the 45 plane of the bases of the teeth of the rack to coöperate with the guide faces on the turn-table, and the other being substantially in the plane of the apexes of the teeth to co-operate with end teeth of the gear in order 50 to prevent the turning of the turn-table after the latter passes out of engagement with the rack.

6. In combination in a paring machine, a main frame, a rotary fork for supporting an 60 apple during the paring thereof, a carriage movable in the direction of the length of the fork, a turn-table mounted on said carriage, driving connection between the turn-table and the main frame, a knife carried by said 65 turn-table, a curved surface having abrupt

ends arranged on the turn-table, and a leaf spring arranged to be engaged by said curved surface and its abrupt ends to hold the turn-table against loose movement at the ends of its movement.

7. In combination in a paring machine, a main frame, a rotary fork, a carriage movable longitudinally of the fork, a turn-table mounted on the carriage and having driving connection with the main frame, a knife arranged on the turn-table, driving mechanism for the carriage having a lost motion connection with the latter, and a spring arranged to act on said carriage when the knife is at or near the inner end of the fork 70 to advance the carriage ahead of the driving mechanism so that the carriage and the knife remain stationary for a short time to flatten the inner end of the fruit.

8. In combination in a paring machine, a main frame, a rotary fork, a carriage movable longitudinally of the fork, a turn-table mounted on the carriage and having driving connection with the main frame, a knife on the turn-table, and driving means for the carriage having provision for permitting the carriage and the turn-table to remain stationary for a short time while the knife is operating on the inner end of the fruit.

9. In combination in a paring machine, a main frame, a rotary fork for supporting the fruit during paring, a carriage movable longitudinally of the fork, a turn-table mounted on the carriage, a knife carried by the turn-table, a rack carried by the main frame, guide face arranged on opposite sides of the rack, a gear on the turn-table, guide faces on opposite sides of the rack for engagement with the guide faces on the main frame when the gear disengages with the rack, said guide faces directing the knife in a line parallel with the axis of the fork before and after the knife has swung in an arc to pare the fruit, and driving mechanism for the carriage having provision permitting the carriage and the turn-table to remain stationary for a short time about the time the gear is to become disengaged from the rack at the inner end of the fork so that the knife operates on the inner end of the fruit 100 to flatten such end.

10. In combination in a paring machine, a main frame, a rotary fork for supporting the fruit during paring, a carriage movable longitudinally of the fork, a turn-table mounted on the carriage, a knife on the turn-table, a gear on the turn-table, two guide faces on opposite sides of the gear, a rack on the main frame for engagement by the gear, two guide faces arranged on opposite sides of the rack for engagement with the guide faces on the turn-table to direct the knife in a line parallel with the fork after the gear has disengaged with the rack, driving means for the carriage having a lost 110 120 125 130 motion connection with the latter, and a leaf spring arranged to be engaged by the curved surface and its abrupt ends to hold the turn-table against loose movement at the ends of its movement.

motion connection with said carriage to permit the carriage to be advanced ahead of the driving power as the knife approaches the inner end of the fruit, and a spring acting to advance the carriage and the turn-table at such point so that they may remain stationary for a short time at this point until the driving means catches up with them.

11. In combination in a paring machine, 10 a rotary fork for supporting the fruit during paring, a knife turn-table movable longitudinally of the fork, a knife depending from said turn-table and having its cutting edge above the axis of rotation of the 15 fork, one side of the knife being recessed below its cutting edge to receive a portion of the fork when the knife operates at the inner end of the fork.

12. A knife for a paring machine having 20 a curved recess in one end for receiving the fork of the paring machine when the knife is operating at the inner end of the fork.

13. A knife head for a paring machine having a curved recess in one side for receiving the fork of a paring machine when the knife is operating at the inner end of the fork.

14. In combination in a paring machine, 30 a rotary support for the fruit, and a knife mounted to move in an arc about the fruit while it is on said support, said knife having its cutting edge operating above the axis of rotation of said fork and being movable to project over a portion of the fork at the 35 inner end of the latter.

15. In combination in a paring machine, a

main frame, a rotary fork for supporting fruit during paring, a carriage movable longitudinally of the fork, a turn-table mounted on said carriage, a knife arranged 40 on the turn-table, driving connection between the turn-table and the main frame, a follower on the carriage, a rotary drum having a way in which the follower operates, said way having a portion which permits 45 the carriage to move relatively to the drum when the knife is approaching the inner end of the fork, and a spring acting to advance the carriage at such point so that the carriage and knife may remain station- 50 ary for a short time.

16. In combination in a paring machine, a main frame, a rotary fork for supporting fruit during paring, a carriage movable 55 longitudinally of the fork, a turn-table mounted on said carriage, a knife arranged on the turn-table, driving connection between the turn-table and the main frame, a follower on the carriage, a rotary drum having a way in which the follower operates, 60 said way having a portion which permits the carriage to move relatively to the drum when the knife is approaching the inner end of the fork, and a spring acting to advance the carriage at such point so that the carriage and knife may remain stationary for 65 a short time, the way having an abrupt shoulder which operates on the follower immediately after said stopping of the carriage so that the knife moves away from the 70 fruit with a quick action.

BURTON C. COONS.
